Adeline E. E. Paterson, Chicago, Ill., assignor to United States Patent Office, Washington, D. C. A. C. 1, filed Dec. 23, 1948, Serial No. 66,998. Patent No. 2,573,806, issued Nov. 6, 1951.

UNITED STATES PATENT OFFICE

2,573,806

UNIDIRECTIONAL RESTRAINING DEVICE FOR A FASTENING CORD

Adeline E. E. Paterson, Chicago, Ill.

Application December 23, 1948, Serial No. 66,998

4 Claims. (Cl. 24—126)

1

This invention relates to a unidirectional restraining device for a fastening cord such as a drawstring, a shoe string, ribbon or the like.

The principal object of the invention is to provide a compact, rugged and simple restraining device for a drawstring or a shoe string, to eliminate tying or knotting of the ends of the string.

Another object is to provide a restraining device which is freely slideable on the cord in the direction of the object which is held closed by the cord, but which is restrained against motion along the cord in the opposite direction and may be easily released by finger pressure.

A further object is to provide a restraining device which does not damage the cord.

The invention is illustrated in a preferred embodiment in the accompanying drawings in which: Fig. 1 is a plan view of the restraining device; Fig. 2 is a side elevation thereof; Fig. 3 is a section taken as indicated at 3—3 of Fig. 2; and Fig. 4 is a section similar to Fig. 3 but showing the spring flexed to release the restraining device for motion along the cord.

Referring to the drawings in greater detail, 5 and 6 are the two ends of a cord to which the restraining device is applied.

As best seen in Fig. 3, the restraining device has a housing 8 which is open at both ends and which has converging side walls 9 and 10 so that it is wedge-shaped, the top and bottom walls 11 and 12 of the housing preferably being parallel. A post 13 extends from top to bottom of the housing, adjacent the smaller end thereof, and is laterally centered therein.

A bifurcated spring, indicated generally at 14, spans the post 13 and has its arms 15 and 16 projecting from the larger end of the housing. The spring is preferably composed of flat spring stock, and as best seen in Fig. 2, the width of each arm of the spring is sufficient that the spring has only slight clearance between the top and bottom walls 11 and 12 of the housing. Thus the spring is freely slideable in the housing, but has little tendency to rock therein. The spring arms are provided with opposed external detents 17 which are positioned between the large end of the housing 8 and the post 13, the detents 17 preferably being formed by bending the spring arms outwardly. The bias of the spring urges the detents 17 toward the converging side walls 9 and 10 of the housing. The projecting ends of the spring arms are curved back, as at 18, to provide suitable finger gripping portions.

After the spring 14 is placed in the housing 8, the top and bottom walls 11 and 12 of the hous-

ing 8 are flanged, at 19 and 20, to prevent the spring from sliding out of the housing through the opening in the small end thereof. Thus the flanges 19 and 20, and the post 13, permit limited longitudinal movement of the spring in the housing.

In using the restraining device, the ends 5 and 6 of a cord, such as a shoelace, are threaded through the opening at the small end of the housing, between the spring arms 15—16 and the side walls 9 and 10 of the housing 8, and out the large end of the housing. Preferably, the tips of the cords are then provided with retaining members such as the balls 21, so that the restraining device may not be inadvertently pulled from the ends of the cord.

The restraining device may be slid freely along the cord until its smaller end is positioned close against the article which is held together by the cord, the motion in this direction being free because the spring 14 is urged toward the large open end of the housing 8, and its motion is arrested by the post 13.

Any force tending to move the restraining device in the opposite direction, so as to loosen the cord, slides the spring 14 toward the small end of the housing by reason of frictional engagement of the cord with the external detents 17. Motion of the cord through the housing in this direction is restrained by cooperation of the detents 17 and the converging side walls 9 and 10. Thus, the greater the force which is exerted, the tighter the cord is gripped by the device. The amount of force which the device can successfully overcome depends upon the smoothness of the cord itself; but even on cords woven from such smooth surfaced fabrics as rayon or nylon, the device can withstand a considerable pull without slipping.

In order to release the restraining device to permit the cord to be loosened, it is merely necessary to press the projecting ends of the spring arms together with the fingers to the position shown in Fig. 4, which allows the device to slide freely so as to permit loosening of the cord.

The foregoing detailed description is given for clearness of understanding only, and no unnecessary limitations should be understood therefrom, as modifications will be obvious to those skilled in the art.

I claim:

1. A unidirectional restraining device for a fastening cord, comprising: a wedge shaped housing having open ends through which the ends of a fastening cord may be threaded, the smaller end

of said housing being flanged; a post in the housing adjacent the smaller end thereof; and a flat bifurcated spring spanning said post and retained for limited movement in said housing by said flanges and said post, the arms of said spring being provided with opposed external detents and having their ends projecting from the large end of the housing.

2. A unidirectional restraining device for a fastening cord, comprising: a wedge shaped housing having open ends through which the ends of a fastening cord may be threaded; and a bifurcated spring mounted in said housing for limited longitudinal motion and having the ends of its arms projecting from the larger end of the housing to provide finger pieces, said spring having an external detent on each arm and being biased to urge said detents toward the converging walls of the housing.

3. A unidirectional restraining device for a fastening cord, comprising: a wedge shaped housing having open ends through which the ends of a fastening cord may be threaded, the smaller end of said housing being flanged; a post in the housing adjacent the smaller end thereof; and a bifurcated spring spanning said post and retained for limited movement in said housing by said flanges and said post, said spring having an external detent on each arm and being biased to

urge said detents toward the converging walls of the housing.

4. A unidirectional restraining device for a fastening cord, comprising: a wedge shaped housing having open ends through which the ends of a fastening cord may be threaded; and a flat bifurcated spring mounted in said housing for limited longitudinal motion, the arms of said spring being outwardly bent to form an external detent on each arm and the spring being biased to urge said detents toward the converging walls of the housing.
